UNITED STATES PATENT OFFICE.

EDWARD B. THORNTON, OF PROVIDENCE, RHODE ISLAND.

DESIGN FOR A STICK OR SCARF PIN.

SPECIFICATION forming part of Design No. 23,716, dated October 23, 1891.

Application filed August 17, 1894. Serial No. 520,631. Term of patent 3½ years.

To all whom it may concern:

Be it known that I, EDWARD BROWN THORNTON, of Providence, in the county of Providence and State of Rhode Island, have 5 invented and produced a new and original Design for Stick or Scarf Pins, of which the following is a specification, reference being had to the accompanying drawing, forming part thereof.

10 The drawing is a side view of a stick or scarf pin showing my design.

The leading feature of my design consists in the lateral projection resembling a cane handle on the upper end of the pin.

15 In the drawing 1 indicates the pin. It is cylindrical in form and pointed at the end. 2 is an enlargement at the upper end of the pin surmounted with a bead. From this ex-

tends upward the foliated-bulb 3 the leaves 6 of which extend above the bead or ring 4. 20 The lateral projection 5 resembling a cane handle is bent at the outer end into the scroll 7, the whole resembling a walking cane which resemblance may be heightened by coloring the pin and the handle differently or making 25 them of metals of different colors.

What I claim is—

The design for a stick or scarf pin substantially as herein shown and described.

In witness whereof I have hereunto set my 30 hand.

EDWARD B. THORNTON.
